FOREIGN PATENT DOCUMENTS

EM 0022199560020 S 4/2013

Primary Examiner — Rashida C. Walshon(74) *Attorney, Agent, or Firm* — Quarles & Brady LLP(57) **CLAIM**

The ornamental design for a shoe, as shown and described.

DESCRIPTION

FIG. 1 is a rear elevational view of an ornamental design for a shoe;

FIG. 2 is a right side elevational view of the shoe of FIG. 1; and,

FIG. 3 is a left side elevational view of the shoe of FIG. 1. The broken lines are included for the purpose of illustrating portions of the shoe that form no part of the claimed design.
